I. J. WEINBERG

MEANS FOR MOTHPROOFING FURNITURE

Filed July 24, 1922

UNITED STATES PATENT OFFICE.

ISSAC J. WEINBERG, OF CHICAGO, ILLINOIS.

MEANS FOR MOTHPROOFING FURNITURE.

Application filed July 24, 1922. Serial No. 577,110.

To all whom it may concern:

Be it known that I, ISSAC JOSEPH WEINBERG, a citizen of the United States, and a resident of Chicago, in the county of Cook and State of Illinois, have invented a new and useful Improvement in Means for Mothproofing Furniture, of which the following is a full, clear, and exact description.

My invention relates to improvements in means for mothproofing furniture, and it consists in the combinations, constructions, and arrangements herein described and claimed.

It is a well known fact that moths enter furniture at the seams of the furniture, and not at the open surfaces of the furniture. In other words, the goods of the furniture is first eaten by the moths at the junction of the various pieces of cloth. It is also well known that the moths hide themselves in the darkest portions of the furniture. It will therefore be apparent that the furniture may be effectively protected if provided with means for killing moths at the junction 25 of the various pieces of goods, i. e., the seams. It is not necessary to mothproof the entire article of furniture as is done in many cases.

The principal object of my invention is to provide a means for moth proofing furniture which may be disposed along the seams of the furniture, thereby effectively protecting the entire article.

A further object is to provide a device of the type described which may be readily secured to the article of furniture as the latter is being manufactured, without the necessity of changing the furniture in the slightest degree.

40 A further object of my invention is to provide a device of the character described which may be disposed in any of the seams of the furniture, thus effectively protecting the same.

45 Other objects and advantages will appear in the following specification, and the novel features of the invention will be particularly pointed out in the appended claims.

My invention is illustrated in the accompanying drawings forming part of this application, in which

Figure 1 is a perspective view of a piece of furniture,

Figure 2 is a vertical section through a piece of furniture,

Figure 3 is an enlarged detail section of

one form of securing adjacent pieces of material together,

Figure 4 is an enlarged detail of another joining of two pieces of cloth, 60

Figures 5, 6, and 7 are still other joinings which are made moth proof, and

Figure 8 is a sectional view of a tassel which has been moth proofed.

In carrying out my invention I make 65 use of a cord or rope 1, which may be made of paper, jute, flax, cloth, or the like, and chemically treat the same so that moths in eating the rope will be killed. This rope is disposed in the various seams of the 70 article of furniture indicated generally in Figure 1, and provides effective means for killing the moths which try to enter the furniture through the seams.

In the drawings I have illustrated my device as being assembled with a sofa, but it is obvious that the device is adapted to be assembled with all types of furniture or like articles which have cloth facing. In ordinary practice, when making the seams 2, 80 (see Figure 1), the cloth portions 3 are sewn into a portion 4 by stitching 5, (see Figure 3). In this way, the seam is provided with a rib-like effect which enhances the beauty of the furniture. 85

In case ordinary rope is desired to be used, I provide a chemically treated tar paper or other chemically treated paper 6, which is disposed around the rope 7, and which protects the latter against moths. The cloth 90 3 and 4 is sewn to the rope 7 by stitching 8, and encloses the paper 6. It is obvious that the paper 6 extends the entire length of the seam, as does the rope 7. In Figure 5 I have shown a slightly modified form of 95 seam, this form differing from the forms shown in Figures 3 and 4 in that the pieces 3 and 4 are disposed around the paper 6. Stitching 8 secures the portion 4 so as to cause it to inclose the rope 7. This type 100 of seam is employed in the front surface of the back of the furniture along the seam 9, (see Figure 1), the seams 10, and in other like places. In other words, wherever a rope seam is desired, I either provide a 105 chemically treated rope 1 or a chemically treated paper 6. Both of these forms perform the same function, and protect the furniture.

In the back of the furniture, the cover 110 3 is secured to a back cover 11. This construction is clearly shown in Figure 7. It

will be noted that the cover 11 is secured to the cover 3 by means of the tacks 12, and that the chemically treated strip 13 is disposed over the heads of the tacks 12 and 5 is enclosed by the cover 11. The strip 13 has been previously chemically treated and therefore kills the moths as they try to enter. The strip 13 also hides the heads of the tacks 12 so as to present a smooth ex- 10 terior to the seam.

Another place which the moths are likely to enter is shown at the junction of the back with the seat of the couch, (see Figure 2). At this place I dispose a chemically treated 15 rope, or a rope which is encased with a chemically treated paper. The rope is covered by denim 14, or other like cloth, which is disposed on the seat of the couch, and which is normally covered by the cushions 20 15. The seam 16 of the denim 14 is moved back into the crevice formed by the back and the seat, and blocks all entrance of the moths therebeyond. It will therefore be apparent that any moths in trying to gain 25 entrance into the couch at this point will have to first eat through the seam 16. Since the seam 16 has been chemically treated, as heretofore described, the moth will therefore be killed before being able to gain entrance into the furniture.

The cushions 15 are also provided with chemically treated seams 17, (see Figure 6). In this case the top cover, 18 and the side cover 19 of the cushions are secured to each 35 other by stitching 20, and have a chemically treated strip 21 disposed therein. The strip 21 extends the entire length of all of the seams in the cushions 15.

From the foregoing, it should be clearly 40 borne in mind that all of the seams of the article of furniture are chemically treated, i. e., have chemically treated material forming a part thereof. In this manner the furniture is protected against moths in as 45 effective a manner as if the entire piece were moth proofed. The furniture with my improved moth proofing process, may be made just as cheaply as is the ordinary furniture. As heretofore stated, the provision 50 of the chemically treated rope or the chemically treated paper provides a seam having the same moth proofing character-

istics. I do not, therefore, desire to be limited to any special type of seam, since it is obvious that various seams can be provided with moth resisting material, and so perform the same function as the type of seam hereabove described. It is obvious that the moth proofing of only the seams is far cheaper than moth proofing the entire 60 article of furniture. As heretofore stated, the moth proofing of the seams protects the furniture just as effectively as if the entire device were moth proof. The article of furniture resembles any ordinary article of furniture, and the moth proofing seams resemble the ordinary seams. The provision of moth-proofed seams does not detract from the appearance of the furniture. The device is simple in construction, and can be readily 70 secured to all types of furniture. It will also be noted that the chemically treated rope or paper can be sewn in the seams in the ordinary manner.

In Figure 8 I have shown a tassel which 75 resembles an ordinary tassel, that is adapted to be secured to an article of furniture. It will be noted that the tassel indicated generally at 30 has a cup-shaped member 31 therein in which the moth killing dis- 80 fectant 32 is disposed. The cup 31 takes the place of the ordinary core which is provided in tassels. It will therefore be understood that the tassel is protected against moths. The tassel is carried by a cord 85 which in turn is secured to an arm of a chair or the like.

I claim:

1. A reenforcing and moth proofing material for cloth covered articles comprising 90 two pieces of cloth, a chemically treated reenforcing member forming a part of the seams of the cloth, stitching securing said member to said cloth, said member adding more material through which the stitching 95 extends, thereby reenforcing the seam.

2. A chemically treated seam comprising a piece of cloth, a chemically treated reenforcing member forming a part of the seam, and stitching securing said member to said cloth, said member adding more material 100 through which the stitching extends, thereby reenforcing the seam.

ISSAC J. WEINBERG.
